US00D957479S

(12) **United States Design Patent** (10) **Patent No.:** **US D957,479 S**
(45) **Date of Patent:** **** Jul. 12, 2022**

(54) **REFRIGERATOR**

- (71) Applicant: **Electrolux Home Products, Inc.**, Charlotte, NC (US)
- (72) Inventors: **Simona Iculano**, Stockholm (SE); **Jerome Esteve**, Stockholm (SE); **Rodrigo Scandelari Pereira**, Stockholm (SE); **Luis Fernando Zeni Filho**, Curitiba (BR); **Gabriel Lied**, Curitiba (BR); **Swaminathan Iyer**, Galaxis (SG); **Ola Lantz**, Galaxis (SG); **Eunice Cheng**, Galaxis (SG)
- (73) Assignee: **Electrolux Home Products, Inc.**, Charlotte, NC (US)
- (**) Term: **15 Years**
- (21) Appl. No.: **29/751,177**
- (22) Filed: **Sep. 18, 2020**
- Related U.S. Application Data**
- (62) Division of application No. 29/661,616, filed on Aug. 29, 2018, now Pat. No. Des. 909,434.

(30) **Foreign Application Priority Data**

(57)

CLAIM

The ornamental design for a refrigerator, as shown and described.

DESCRIPTION

FIG. 1 is a front perspective view of a refrigerator showing our new design;

FIG. 2 is a front view thereof;

FIG. 3 is a left side view thereof;

FIG. 4 is a right side view thereof;

FIG. 5 is a top view thereof;

FIG. 6 is a front perspective view of a second embodiment of a refrigerator;

FIG. 7 is a front view thereof;

FIG. 8 is a left side view thereof;

FIG. 9 is a right side view thereof; and,

FIG. 10 is a top view thereof.

The broken lines depicting the ice dispenser of the refrigerator in FIGS. 6-7 form no part of the claimed design.

1 Claim, 10 Drawing Sheets
